UNITED STATES PATENT OFFICE.

JAMES T. HAMBAY, OF WILKINSBURG, ASSIGNOR TO THE UNION SWITCH AND SIGNAL COMPANY, OF PITTSBURG, PENNSYLVANIA.

SWITCH AND SIGNAL APPARATUS.

SPECIFICATION forming part of Letters Patent No. 406,213, dated July 2, 1889.

Application filed February 21, 1889. Serial No. 300,707. (No model.)

To all whom it may concern:

Be it known that I, JAMES T. HAMBAY, a citizen of the United States, residing at Wilkinsburg, in the county of Allegheny and State of Pennsylvania, have invented or discovered certain new and useful Improvements in Switch and Signal Apparatus, of which improvements the following is a specification.

The invention described herein relates to certain improvements in switch and signal operating apparatus, and has for its object the application of a preliminary lock to that class of switch and signal apparatus known as the "horizontal-lever" machines.

In general terms, the invention consists in the construction and combination of mechanical devices, all as more fully hereinafter described and claimed.

In the accompanying drawings, forming a part of this specification, Figure 1 is a view of a machine in side elevation embodying my invention. Fig. 2 is a top plan view of the same. Fig. 3 is a view partly in section and partly in end elevation of the machine, and Fig. 4 is a sectional elevation showing the relative arrangement of the machines and their interlocking mechanism where two or more such machines are included in a plant or apparatus.

Upon a shaft 1, supported in suitable bearings in the frame 2, are loosely mounted the wheels 3, which are connected to the switches or signals by a chain or other flexible connection 4, secured in a groove formed in the faces of the wheels or by a rack-bar engaging teeth formed on the perimeter of said wheels. These wheels are rotated by the levers 5, loosely mounted on the shaft 1 outside of the wheels and attached to said wheels by suitable bolts or otherwise. These levers are provided with spring latches or catches 6, controlled by the levers 7, arranged in convenient proximity to the handles of the levers 5, the blocks 8 of said latches being arranged to engage notches 9 in the edges of the frame 2, as shown in Fig. 1. To the blocks 8 are attached rods 10, arranged alongside of the levers 5 and made of sufficient length to project beyond the axis of the shaft 1 when the blocks are in engagement with the notches 9

an amount equal to the length of stroke of the latches. The inner or free ends of the rods 10 are connected to arms of bell-crank levers 11, preferably pivoted in the vertical plane passing through the axis of the shaft 1. The other arms of the bell-crank levers 11 are connected to bars 12, mounted in guides on the bracket 13, attached to the under side of the frame 2. A locking-pin 14 is mounted transversely of the bars 12 in guide-grooves in the bracket, said pin being of a length a little greater than the distance between the bars 12, which have V-shaped notches 15, formed at suitable points in their inner edges for the reception of the correspondingly-shaped ends of the pin 14.

In operating my improved machine, the block 8 of one of the levers 5^a—as, for example, the right-hand lever in Fig. 3—is withdrawn from its notch 9, thereby pulling the end of the upper arm of the bell-crank 11^a into line with the axis of the shaft 1, and the lever 5^a is raised until the block 8 engages the notch 9^a, which is not sufficiently deep to permit of such movement of the block 8^a as will throw the upper end of the bell-crank lever 11^a out of line with the axis of the shaft 1. This movement of the bell-crank lever 11^a so shifts its bar 12^a as to bring the notch 15^a in line with the pin 14, which previous to the movement of the lever 5^a was in engagement with the notch 15 of the bar 12, thereby locking said bar. The lever 5 is now shifted, the block 8 being first disengaged from its notch 9, thereby shifting the bell-crank lever 11 and the bar 12 entirely over until the block engages the notch 9 on the opposite side of the frame. The movement of the bar 12 incident to the disengagement of the block 8 from its notch shifts the pin 14 into engagement with the notch 15^a of the bar 12^a, thereby locking said bar and its lever from any movement until the block 8 enters one of the notches 9, whereupon the bar 12 will be again shifted by the movement of the upper end of the bell-crank lever 11 out of line with the axis of the shaft 1, thereby bringing its notch 15 again into line with the pin 14. The movement of the lever 5^a is now completed, and its block 8^a enters the notch 9^a, thereby shifting 100

the bell-crank lever 11^a and bar 12^a. The movement of the bar 12^a shifts the pin 14 into engagement with bar 12 and locks said bar and its operating-lever.

5 In practice two or more of the machines consisting of two levers and their interlocking devices are arranged alongside of each other, as shown in Fig. 4, a sufficient space being left between adjacent machines for the passage 10 of the operator from one side to the other for the purpose of operating the levers. As shown, each machine has only two levers, and by spacing the machines as stated the operator is afforded room for the movements 15 necessary in operating the levers. The bars 12 of each machine are interlocked with the bars of the other machines by a series of pins 14, the combinations formed being dependent upon the number of switches and signals in 20 operation and the order and relation of their movements to each other.

I claim herein as my invention—

1. In a horizontal-lever machine for oper-

ating switches and signals, the combination of an operating-lever, a movable block for locking the lever, a bell-crank lever having one of its ends connected to said block and movable thereby into and out of line with the center of movement of the lever, and an interlocking mechanism operated by the bell-crank, substantially as set forth. 25

2. In a switch and signal apparatus, a series of two or more horizontal-lever machines separated to form a passage-way between adjacent machines, each machine having two levers interlocked with each other, in combination with interlocking mechanism for interlocking the levers of one machine with those of another machine, substantially as set forth. 35

In testimony whereof I have hereunto set 40 my hand.

JAMES T. HAMBAY.
